CLAIM

The ornamental design for a toilet flush handle, as shown
and described.

DESCRIPTION

FIG. 1 is an oblique view of a toilet flush handle showing my
new design.

FIG. 2 is an environmental view thereof.

FIG. 3 is a front elevation thereof.

FIG. 4 is a rear elevation thereof.

FIG. 5 is a right side elevation thereof.

FIG. 6 is a left side elevation thereof.

FIG. 7 is a top plan view thereof; and,

FIG. 8 is a bottom plan view thereof.

The broken line showing is for illustrative purposes only and
forms no part of the claimed design.
